UNITED STATES PATENT OFFICE.

SAMUEL MCKITTRICK, OF SANDUSKY, OHIO.

FLY-TRAP.

1,087,964.

Specification of Letters Patent.

Patented Feb. 24, 1914.

Application filed January 23, 1913. Serial No. 743,865.

To all whom it may concern:

Be it known that I, SAMUEL MCKITTRICK, a citizen of the United States, residing at Sandusky, in the county of Erie and State 5 of Ohio, have invented a new and useful Fly-Trap, of which the following is a specification.

The device forming the subject matter of this application, is a trap adapted to be employed for catching flies and other insects.

One object of the present invention is to provide novel means for separating the interior of the case of the trap into a poisoning chamber and a receiving chamber, the 15 separation of the interior of the case into these chambers being effected by the coöperation between a poison receptacle and a drum engaging scraper.

Another object of the invention is to improve generally, and to increase the utility of, devices of that type to which the present invention appertains.

With the foregoing and other objects in view which will appear as the description 25 proceeds, the invention resides in the combination and arrangement of parts and in the details of construction hereinafter described and claimed, it being understood that changes in the precise embodiment of invention can be made within the scope of what is claimed without departing from the 30 spirit of the invention.

In the drawing:—Figure 1 shows the invention in top plan; Fig. 2 is a longitudinal 35 section; Fig. 3 is an end elevation; Fig. 4 is a perspective of the scraper.

In carrying out the invention there is provided a case 1, into one end of which is removably inserted a drawer 2. Disposed 40 transversely of the case 1 and terminally journaled in the side walls of the case 1 is a shaft 3, secured to a drum 4, provided upon its periphery with a plurality of outstanding ribs 5. The side walls of the case 1 are cut 45 away at one end, as indicated at 6, so that the periphery of the drum 4 may be exposed. Mounted upon one side wall of the case 1 is a clock motor 7, or a prime mover of any other desired sort, the motor 7 being operatively 50 connected with one end of the shaft 3, to drive the shaft 3 and to rotate the drum slowly. Mounted upon the upper edges of the side walls of the case 1 are guides 8, receiving plate 9 which preferably is fashioned 55 from glass. The plate 9 is located relatively close to the circumference de-

scribed by the outer ends of the ribs 6, so that when the drum 4 is rotated, the outer ends of the ribs 6 move in close proximity to the plate 9. The upper edges of the side walls of the case 1 are further provided with guides 10, receiving removably, a transparent plate 11, the plates 9 and 11 abutting, as clearly shown in Fig. 2, so as to effect a closure of the rear, upper portion of the 35 case 1.

In the rear wall of the case 1, there is an opening 12, receiving a poison receptacle 14, provided with a top 14'. The receptacle 14 is of wedge-shape and is received between 70 spaced, converging guides 15 which are secured to the side walls of the case 1. The top of the receptacle or reservoir 14, is denoted at 14^b and in the top 14^b there is a transverse slot 17. The top 14^b of the reservoir 75 14 carries a filling tube 16. A strip 18 of absorbent material rests at one end upon the top 14^b of the reservoir or receptacle, the other end of the strip 18 extending into the interior of the reservoir or receptacle 14, 80 through the slot 17.

The invention further includes a scraper 19 provided with upstanding arms 20, secured by means of pivot elements 21, to the side walls of the case 1. The scraper 85 19 is so mounted that it will hang gravitationally against the periphery of the drum 4, between the ribs 5. However, when the drum 4 is rotated through the medium of the motor 7, the scraper 19 will engage 90 with the ribs 5. It is to be noted that the scraper 19 serves to bridge the space between the drum 14 and the inner end of the receptacle or reservoir 14. Thus, the scraper 19, and the member 14 coöperate to 95 divide the interior of the case 1 into a poisoning chamber 22 and a storage chamber 23.

In practical operation, the periphery of the drum 4 is smeared with an attractive 100 bait, the drum being rotated slowly through the medium of the motor 7. The insects which light upon the periphery of the drum, are carried slowly beneath the plate 9, and it is to be observed that the ribs 5, successively, constitute closures for the space existing between the periphery of the drum 4 and the plate 9 so that the insects cannot escape rearwardly. The insects are thus carried into the poisoning chamber 22, the 110 air within which is saturated by the absorbent member 18, the same being adapted

to soak up any liquid which may be placed within the receptacle 14, through the medium of the filling tube 16. When the drum 4 is rotated, the scraper 19 will engage the periphery of the drum, to remove the dead insects, the same dropping downward into the storage compartment chamber 22. The drawer 2 may be removed at any time, a cleaning out of the device being thereby effected.

It is to be observed that the wedge-shaped reservoir 14 coöperates with the converging guides 15, so that, when the reservoir is inserted into the case through the opening 12, the inner end of the reservoir will be positioned properly with respect to the scraper 19, so as to permit a pivotal movement of the scraper upon its mounting 21.

Having thus described the invention, what is claimed is:—

1. An insect trap comprising a case; a drum journaled in the case; a poison receptacle in the case and dividing the case into a poisoning chamber and a storage chamber; and a movable drum-engaging scraper pivotally supported in the case and coöperating with the receptacle to separate the poison chamber from the storage chamber.

2. An insect trap comprising a case; a drum journaled in the case; a poison recep-

tacle located in the case and dividing the case into a poisoning chamber and a storage chamber; and a movable drum-engaging scraper in the case, coöperating with the receptacle to separate the poisoning chamber from the storage chamber; the receptacle being removable, and there being an element upon the case, engaging the receptacle to limit inward movement of the receptacle and to space the same from the scraper.

3. An insect trap comprising a case; a drum journaled in the case; a poison receptacle located in the case and dividing the case into a poisoning chamber and a receiving chamber, the receptacle being provided with a top having a slot; an absorbent element supported by the top and extended into the slot; and a movable drum-engaging scraper supported in the case and coöperating with the receptacle to separate the poisoning chamber from the receiving chamber.

In testimony that I claim the foregoing as my own, I have hereto affixed my signature in the presence of two witnesses.

SAM. McKITTRICK.
